CLAIM

The ornamental design for a toy motorcycle, as shown and described.

DESCRIPTION

FIG. 1 is a top plan view of a first toy motorcycle in accordance with my new design;

FIG. 2 is a bottom plan view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a right side elevation view of a second toy motorcycle in accordance with my new design, the top, bottom, front and rear views being the same as FIGS. 1 through 4 and the left side elevation view being the same of one of FIG. 6 and a mirror image of FIG. 7.

FIG. 8 is a top plan view of a third toy motorcycle in accordance with my new design;

FIG. 9 is a bottom plan view thereof

FIG. 10 front elevation view thereof

FIG. 11 is a rear elevation view thereof, the right and left side elevation views thereof being the same as FIGS. 5 and 6 or FIGS. 7 and 6, respectively;

FIG. 12 is a top plan view of a fourth toy motorcycle in accordance with my new design;

FIG. 13 is a bottom plan view thereof

FIG. 14 front elevation view thereof

FIG. 15 is a rear elevation view thereof;

FIG. 16 is a right side view thereof;

FIG. 17 is a left side view thereof; and,

FIG. 18 is a right side elevation view of a fifth toy motorcycle in accordance with my new design, the other views being the same as FIGS. 12–15 and 17 or FIGS. 12–15 and a mirror image of FIG. 18.
